HEADLIGHT SHIELD

Filed Aug. 26, 1926

FIG. 1.

FIG. 2.

Inventor

L. E. McAllister

By

Lacey & Lacey, Attorneys

UNITED STATES PATENT OFFICE.

LEMUEL E. McALLISTER, OF QUINCY, ILLINOIS.

HEADLIGHT SHIELD.

Application filed August 26, 1926. Serial No. 131,715.

This invention relates to headlights and more particularly to a reflector shield.

One object of the invention is to provide a shield by means of which certain portions 5 of a reflector may be guarded and prevented from projecting a blinding light into the eyes of the driver of an approaching vehicle.

Another object of the invention is to so construct the shield that it may be held in 10 place by the bulb and a portion of the shield pressed firmly into engagement with the reflector in order to prevent the shield from moving out of its proper position in the headlight.

15 Another object of the invention is to provide a shield which will prevent light rays from being projected upwardly into the eyes of an approaching pedestrian or vehicle driver and still permit proper illumination 20 of the roadway.

Another object of the invention is to make it unnecessary to alter the construction of a conventional headlight in order to apply the shield to it.

25 The invention is illustrated in the accompanying drawing, in which

Figure 1 is a vertical sectional view through a headlight of a conventional construction having one of the improved shields 30 applied to it, and

Fig. 2 is a perspective view of the improved shield.

The shield constituting the subject-matter of this invention is intended to be applied to 35 a conventional form of headlight such as shown in Fig. 1 and indicated in general by the numeral 1. The headlight includes the usual reflector 2 carrying a socket 3 into which is removably fitted the shank 4 of a bulb 5. The usual wires 6 lead from the socket 3 to a suitable source of current. Under ordinary conditions, the lower portion 40 of the reflector causes light rays to be directed upwardly into the eyes of the driver of an approaching automobile and the central portion of the reflector to the rear of and immediately surrounding the bulb causes the formation of a "bull's eye" which is projected forwardly a very great distance and 45 is very blinding. In order to cover the central portion of the reflector and lower portion thereof, I have provided a reflector which is constructed, as shown in Fig. 2, and mounted in the headlight, as shown in 55 Fig. 1. The guard plate 7 which serves to prevent the projection of light rays by the

lower portion of the reflector together with its attaching plate 8 are preferably formed as a unit and stamped from sheet metal, although other materials may be employed if 60 so desired. The side portions of the guard plate are severed from the attaching plate and bent upwardly to form flanges 9 which increase in depth towards their forward ends and at their forward ends are curved so that they merge into the concaved forward edge 10 of the guard plate. The guard plate is of such length that, when the shield is applied to the headlight, it will project forwardly beyond the bulb a sufficient distance to prevent the rays of light from the bulb striking the lower portion of the reflector. A mounting disk 11 which is preferably formed of cardboard, although other materials may be used, fits against the inner face of the attaching plate 8 and is firmly secured to it by tongues 12 which project from the attaching plate and are bent over the peripheral edge of the mounting disk and into firm gripping engagement with its rear face. In the present illustration, the attaching plate has been shown triangular in shape and the mounting disk circular, but it will be understood that both could be circular or other shapes if so desired. An opening 13 is formed centrally 70 in the attaching plate 8 and registers with an opening 14 formed in the mounting disk. It should be noted that the opening in the attaching plate is larger than the opening in the mounting disk and that the outer portion 80 of the opening 14 increases in diameter in order to form an annular shoulder 15 for engagement by the bulb 5. The shoulder 15 is preferably formed by pressing the material of the disk about the opening 14 rearwardly during or after formation of the opening.

When the shield is to be applied, the bulb 5 is removed from its socket 3 and its shank passed through the opening 14. The shank 100 of the bulb is then inserted into its socket 3 and when turned or screwed firmly into place the bulb will engage the annular shoulder 15 and force the marginal portions of the mounting disk into tight binding engagement with the central portion of the reflector. The disk is of sufficient diameter to cover the central portion of the reflector rearwardly of and immediately surrounding the bulb and, therefore, that portion of the 110 reflector which causes the formation of a bull's eye will be hidden and rendered inop-

erative. Therefore, the formation of a bright light which normally projects a great distance ahead of an automobile and tends to blind an approaching driver is eliminated. The guard plate projects forwardly beneath and beyond the bulb and serves to guard the lower portion of the reflector and prevent this portion of the reflector from directing light rays upwardly into the eyes of an approaching driver but it does not prevent the remainder of the reflector from projecting light rays towards the sides of the automobile and downwardly in front of it. The roadway may, therefore, be well lighted at the sides of an automobile and for some distance ahead of it. If it is desired to use the headlights without the guards, they may be very easily and quickly removed or they may be removed from the headlights of one automobile and transferred to the headlights of another automobile.

Having thus described the invention, I claim:

1. A reflector shield comprising a mounting disk formed with an opening adapted to receive the shank of a bulb, the opening having its inner portion of an even diameter and its outer portion flaring towards its outer end to provide with an annular shoulder to be engaged by a bulb having its shank passed through the opening, and a guard plate projecting from the lower portion of said mounting and adapted to extend beneath a bulb.

2. A reflector shield comprising a mounting disk formed with an opening to receive the shank of a bulb when mounting the shield in a headlight, said disk being of sufficient size to cover the portion of a headlight

reflector to the rear of and immediately surrounding a bulb, and a guard plate projecting forwardly from the lower portion of said disk and adapted to extend beneath a bulb and project forwardly therefrom and increasing in width towards its front end and 45 formed with a concaved forward edge, the side portions of the guard plate being provided with upwardly extending side flanges gradually increasing in depth from their rear ends towards their forward ends. 50

3. A reflector shield comprising a mounting disk formed with an opening to receive the shank of a bulb when mounting the shield in a headlight, said disk being circular in shape and of sufficient diameter to cover the portion of a headlight reflector to the rear of and immediately surrounding a bulb, a guard plate projecting forwardly from the lower portion of said disk and adapted to extend beneath a bulb and project forwardly therefrom and increasing in width towards its front end, an attaching plate formed integral with and projecting upwardly from the rear end of said guard plate, the attaching plate being triangular 65 in shape and disposed against the outer face of said disk and provided with an opening registering with but of greater diameter than the opening in the disk, and tongues projecting from the corner portions of said attaching plate and folded across the outer marginal edge of said disk into engagement with the inner face thereof to securely retain the attaching plate in engagement with the disk. 70

In testimony whereof I affix my signature.

LEMUEL E. McALLISTER. [L. S.]
